RECEPTACLE HOLDER

Harvey L. Glidden, Lexington, Mass., assignor to
 United Shoe Machinery Corporation, Paterson,
 N. J., a corporation of New Jersey

Application December 8, 1933, Serial No. 701,546
 In Great Britain January 2, 1933

8 Claims. (Cl. 91—57)

This invention relates to agitating devices and is herein illustrated as embodied in a holder for liquid receptacles.

Prior to using paints, stains, shoe dressings, and other liquids employed, for example, in the finishing of shoes or shoe parts, it is frequently necessary to agitate the liquid in order to render it homogeneous. One method employed in shoe factories for doing this consists in placing the receptacle containing the liquid upon a pair of horizontal rotary shafts which are operated by friction to rotate the receptacle thereby agitating its contents. This method is effective but heretofore has been limited to use in connection with cylindrical receptacles.

An object of the present invention is to provide a holder for the receptacles having flat sides whereby rotation of the receptacles in devices of the kind aforementioned is made possible. To this end and as illustrated, the invention provides a holder having spaced annular end portions and members extending between the annular end portions adapted to engage the flat sides of a receptacle whereby the receptacle can be rotated upon rotation of the holder.

Other objects and features of the invention will be apparent from the following detailed description when taken in connection with the accompanying drawing and will be pointed out in the claims.

In the drawing,

Fig. 1 is a perspective view of an agitating device having in position thereon one form of holder constructed according to the invention;

Fig. 2 is a perspective view of another form of holder and receptacle; and

Figs. 3 and 4 are end views of the holder shown in Fig. 1 with receptacles of different shapes positioned therein.

The form of receptacle holder illustrated in Fig. 1 is particularly adapted for facilitating the rotation of receptacles of either square or oblong cross-sections. This holder 10 is constructed of metal rods or heavy wire and comprises two rings 12 which are connected by two pairs of resilient ribs 14 and 16, opposite ends of the ribs 14 and 16 being soldered or welded respectively to the rings 12. Each of the members 14 and 16 is curved inwardly along a plane passing through the axis of the device, is adapted to engage the side of a flat-sided receptacle such as a can 18, and is sufficiently resilient to yield outwardly to permit insertion of receptacles of various sizes and shapes. In holding receptacles of square cross section, each side of the recep-

tacle is, as illustrated at 19 in Fig. 3, engaged by one of the ribs 14 or 16. In holding receptacles of oblong cross section, it has been found preferable to insert the receptacle with its longer axis lying between the two pairs of ribs 14 and 16 as shown in Figs. 1 and 4. In this way the pairs of ribs 14 and 16 will engage respectively opposite sides of the receptacle with a minimum spreading of the ribs. In order to eliminate any tendency of such receptacle to move radially of the holder in a direction parallel to the sides which are engaged by the ribs 14 and 16, there are provided additional ribs 20 adjacent, respectively, to one of the members 14 and to one of the members 16 adapted to engage the other 15 two sides of the receptacle. The construction above described thus provides a holder which is adaptable for use in holding flat-sided receptacles of many standard shapes and sizes, the receptacle in each case being held within the 20 generally cylindrical structure bounded by the rings 12 which constitute outwardly disposed annular portions by which the holder can be rotated.

Another form of holder particularly adapted for use in holding comparatively large and heavy receptacles of square cross section is illustrated in Fig. 2. This holder 21 comprises end pieces each composed of an outer ring 22 and an inner ring 24 which are connected by means of longitudinally extending ribs 26 having bent portions 28 which are soldered or welded to the rings 22 and 24. The receptacle engaging members comprise wire loops 30 the legs of which are secured to the rings 22 and 24 and which extend first 35 inwardly of the ring members and then outwardly, thus to form curved receptacle engaging portions 32. Each leg of the loop 30 is bent to form small loops 34 which render the loops 30 yieldable outwardly of the central portions of 40 the structure. The loops 30 are braced by wire members 36 secured to the members 26 and to the legs of the loops 30. Preferably, the loops 30 are arranged in pairs about the periphery of the device and each pair of loops is adapted to engage one side of a receptacle such as receptacle 38 forced axially through the ring members. The pairs of loops 30 engage all four sides of the receptacle near opposite ends thereof thus to secure it firmly in position within the holder.

The holders 10 and 21 are utilized in connection with the agitation of liquids in the receptacles positioned in the holders in agitating devices such as that illustrated in Fig. 1. As shown, the agitating device comprises a frame 40 which 55

carries a pair of horizontal parallel shafts 42 and 44. The shaft 42 is driven by pulley 46 and the shaft 44 is driven in the same direction by a belt 48 which passes over a pulley 50 on shaft 5 42 and a pulley 52 on shaft 44.

The shafts 42 and 44 are provided with collars 54 having grooves 56 which are arranged to engage the rings 12 of the holder 10, as shown in Fig. 1, or the rings 22 of the holder 21 to rotate by frictional contact the holder and the receptacle therein.

Having described my invention, what I claim as new and desire to secure by Letters Patent of the United States is:

15. 1. A receptacle holder comprising a plurality of spaced rings, and members positioned inwardly of the peripheries of the rings for engaging and gripping opposite sides of a flat-sided receptacle.
20. 2. A receptacle holder comprising a plurality of spaced rings, and resilient ribs connecting the rings, each of the ribs being curved inwardly to engage a side of a receptacle positioned within the holder.
25. 3. A receptacle holder comprising two spaced annular members, and a plurality of pairs of resilient members connecting the annular members and curved inwardly of the peripheries of the annular members to engage oppositely disposed sides of a flat-sided receptacle, and addi-

tional resilient members for engaging other sides of the receptacle.

4. A holder for flat-sided receptacles comprising spaced annular members, and a plurality of yieldable ribs connecting the annular members and curved inwardly toward the axes of the members for engaging the side walls of a receptacle.

5. A holder comprising a pair of spaced rings, and members extending between the rings having resilient curved inwardly extending portions for 10 engaging the sides of a receptacle.

6. A holder comprising a plurality of spaced rings and pairs of resilient members secured to the rings along the peripheries thereof and having curved portions for engaging a receptacle 15 positioned in the holder.

7. A holder comprising a plurality of rings, ribs connecting the rings and having inwardly disposed portions for engaging the sides of a receptacle, the ribs being arranged in pairs each pair 20 of which is arranged to engage one of two opposite sides of a receptacle, and an additional rib for engaging an adjacent side of the receptacle.

8. A device for holding receptacles comprising a plurality of spaced annular members, ribs connecting the members, each of said ribs being curved inwardly toward the axis of the device and lying in a radial plane for engaging opposite sides of a flat-sided receptacle, and additional ribs for engaging other sides of the receptacle.

30. HARVEY L. GLIDDEN.
